(57) **CLAIM**

The ornamental design for a air inlet with integrated fluid diverter, as shown and described.

DESCRIPTION

FIG. 1 is a front perspective view of an air inlet with an integrated fluid diverter from above;

FIG. 2 is a rear perspective view of the air inlet with an integrated fluid diverter;

FIG. 3 is a front perspective view of the air inlet with an integrated fluid diverter from below;

FIG. 4 is a side perspective view of the air inlet with an integrated fluid diverter from the right;

FIG. 5 is a bottom side view of the air inlet with an integrated fluid diverter;

FIG. 6 is a top view of the air inlet with an integrated fluid diverter; and,

FIG. 7 is a bottom view of the air inlet with an integrated fluid diverter.

In FIGS. 1-7, broken lines indicate environmental structure that forms no part of the claimed design.
